UNITED STATES PATENT OFFICE.

CHARLES W. MCKINLEY, OF WASHINGTON, DISTRICT OF COLUMBIA, AND HARRY H. GOODALL, OF TOLEDO, OHIO, ASSIGNEES TO THE WILLYS-OVERLAND COMPANY, OF TOLEDO, OHIO, A CORPORATION OF OHIO.

DESIGN FOR AN AUTOMOBILE-BODY.

53,927.

Specification for Design.

Patented Oct. 7, 1919.

Original application filed June 15, 1917, Serial No. 175,035. Divided and this application filed July 19, 1918. Serial No. 245,768. Term of patent 14 years.

To all whom it may concern:

Be it known that we, CHARLES W. MCKINLEY and HARRY H. GOODALL, citizens of the United States, and residing, respectively, in the city of Washington, District of Columbia, and the city of Toledo, county of Lucas, State of Ohio, have invented a new, original, and ornamental Design for Automobile-Bodies, of which the following is a specification, reference being had to the accompanying drawing, forming part thereof.

The figure is a perspective view of the automobile body showing our new design.

This application is a division of our prior application, Serial No. 175,035, filed June 15, 1917, for a design for an automobile.

We claim—

The ornamental design for an automobile body as shown.

In testimony whereof we affix our signatures.

CHARLES W. MCKINLEY.
HARRY H. GOODALL.
